INVENTOR
Robert G. Hopkins.

UNITED STATES PATENT OFFICE.

ROBERT G. HOPKINS, OF SOMERVILLE, ASSIGNOR, BY MESNE ASSIGNMENTS,
TO CARTER'S INK COMPANY, OF BOSTON, MASSACHUSETTS.

INKSTAND.

SPECIFICATION forming part of Letters Patent No. 554,424, dated February 11, 1896.

Application filed July 21, 1894. Serial No. 518,188. (No model.)

To all whom it may concern:

Be it known that I, ROBERT G. HOPKINS, a citizen of the United States, residing at Somerville, in the county of Middlesex and State of Massachusetts, have invented a new and useful Improvement in Inkstands, of which the following is a full, clear, and exact description, reference being had to the accompanying drawings, forming a part of this specification, in explaining its nature.

The invention is an improvement upon that type of inkstand known as the "automatic inkstand" and in which a small receptacle at the upper end of a movable tube supplies the ink being used.

It consists in applying preferably to an inkstand of this character a device whereby the diaphragm of the stand is caused to be moved downward and held downward, whereby the ink is subjected to such pressure that it is caused to flow upward through the tube and fill the small receptacle and maintain it filled for awhile, and when emptied the diaphragm is raised and the process repeated. When this device is applied to an automatic inkstand it may be used in its usual way, which requires a downward movement of the small receptacle and tube for substantially each dip of the pen, or it may be used as above indicated.

In the drawings, Figure 1 is a view, in vertical central section, of an inkstand having the features of my invention, representing the supplemental or additional ink-fount in its elevated position or that which requires a downward movement for each dip of the pen; and Fig. 2 represents the supplemental fount in its depressed condition, or that in which it is filled and maintained filled until the ink has been exhausted from it.

A represents the inkstand proper. It has a reservoir a , which is adapted to hold a relatively large supply of ink. It is open at its top and has about its upper edge at the top the screw-thread a' upon which screws a cap B , the cap holding upon the upper edge a^2 of the main stand by its edge the flexible diaphragm C , preferably arched upward in place.

This diaphragm supports the movable tube E which extends downward into the ink-well and upward through the cap, its upper end supporting or forming the ink-fount E' .

The cap B has a central hole b , in which screws an adjusting-nut F , and the cap may have the thread formed by its edge alone, or it may have a downward-extending section b' , in which the thread is formed. The nut F has a thread f to engage the edge of the cap about the hole or the threaded section thereof, and also an outwardly-extending flange f' above the cap, which furnishes means by which it may be readily turned. It has a hole f^2 , through which the tube E extends and in which it is vertically movable.

When the nut is in its highest position, the tube and fount E' may be moved downward at each dip of the pen and the fount filled and emptied at each dip. By screwing the nut downward it comes into contact with the diaphragm C , depresses it and the tube E and the fount E' , and thereby fills the tube and the fount and by holding the tube and fount depressed maintains them filled.

I would not be understood as limiting the invention to a stand having an arched diaphragm, as it may be employed in connection with a stand having any sort of a diaphragm the movement of which causes the level of the ink in the stand to be changed, and I would state that the adjusting device may bear upon the diaphragm directly as well as upon the movable tube, in which event the tube and small fount may be stationary and only the diaphragm moved.

Having thus fully described my invention, I claim and desire to secure by Letters Patent of the United States—

1. The combination of the ink-vessel A , the tube and fount supporting diaphragm C , the cap B screwing upon the vessel A and having the hole b , the nut F screwing in said hole and adapted to depress the diaphragm and tube when desired to fill and maintain filled the ink-fount, as and for the purposes described.

2. The combination of the ink-vessel A , the diaphragm C , the nut F having the hole f^2 and the tube E having the fount E' , as and for the purposes described.

ROBERT G. HOPKINS.
